ANTENNA

Michael D. Ercolino, Wanamassa, N. J.

Application August 18, 1949, Serial No. 110,988

3 Claims. (Cl. 250—33.65)

1

This invention relates to high frequency antennas and more particularly to antennas generally employed for television, frequency modulation, and other high frequency systems. This application is a continuation in part of my prior application Serial No. 67,360, filed December 27, 1948, now Patent No. 2,518,297, granted August 8, 1950.

In my previous application, I illustrated and described a dipole antenna wherein a pair of fed dipole rods were tilted or inclined forward so that, under a considerable range of frequencies, the energy became additive and in phase, the lobe sharpening and remaining in line over a wide band such as is required for television receiving purposes. It was further pointed out that the antenna, with its dipole arms inclined forwardly, was particularly efficient when in the form of crossed dipoles which simulate the action of solidly spun cones without involving the bulk of such cones. It will be recognized that the effect thereof is to render the center impedance substantially constant.

In the antenna of my previous application, although the front or fed dipole elements were inclined forwardly, the reflector elements were in alignment. This created a condition where the effective distance between the fed dipoles and the reflector increased from the apex of the V formed between inclined dipoles to the ends thereof. It is recognized in the art that the reflector should be spaced about a quarter of a wave length from the fed elements. By forming the fed elements in the shape of a V with the apex nearest the reflector, the arms diverged outwardly relative thereto. As a result, as the frequencies accommodated became higher, the effective distance between the V-shaped fed dipole structure and the reflector structure increased. Such a system provides high gain because losses at lower frequencies due to the proximity of the reflector are minimized.

The present application further amplifies the above mentioned advantages by inclining the reflector rearwardly whereas the fed structure is still inclined forwardly. It has been found that the effective distance between the fed elements and the reflector is rendered so proportional to the range of frequencies accommodated that the gain of the overall structure is considerably increased. This result has been effected by bending the rear bracket rearwardly so that the reflector elements are no longer in alignment but diverged outwardly relative to the fed antenna elements.

2

The invention will be further understood from the following description and drawings in which:

Fig. 1 is a top view of an antenna structure constructed according to the principles of the instant invention.

Fig. 2 is an enlarged view of the rear bracket which supports the reflector dipole arms.

Fig. 3 is a cross-sectional view as taken along the lines 3—3 of Fig. 2.

Fig. 4 is a cross-sectional view as taken along the lines 4—4 of Fig. 2.

In the form shown the antenna comprises a cross beam 10 having U-shaped end members 11 and 12. Member 12 supports an insulation block 13 upon which the front or fed dipole is effectively mounted. The mounting is accomplished by brackets 14 and 15, both of which are secured to insulator 13 and comprises opposing and complementary bracket members which are bolted together so as to clamp the dipole arms 16 and 17 respectively. The dipole arms 16 are in the form of a V as are the dipole arms 17. The apices of each such V are in the same horizontal plane and are inclined toward each other as will be understood from the illustrated inclination of the dipole arms. The detailed construction of such front brackets 14 and 15 were set forth in my prior, above mentioned application. A mast 18 and clamping bracket 19 serve to support the cross beam in its useful, elevated position as will be well understood by those skilled in the art.

Rear bracket 20 is essentially a three-piece construction. Thus, it comprises a unitary rear bracket 21 and two, somewhat triangular front brackets or plates 22 and 23. The plates are maintained in position by bolts 24 disposed in the three openings 25 of the plates 22 and 23 and the complementary six openings of rear plate 21.

The outer margins or legs 26 and 27 of front bracket member or plate 22 are shaped so as to be concavo-convex. The adjacent margins of plate 21 are similarly formed with concavities 28 and 29 so as to form a pair of diverging channels between plates 21 and 22. Plate 23 and the adjacent portion of plate 21 similarly form a second pair of diverging channels. It is into these channels that the dipole arms are inserted and thereafter clamped.

Before applying the dipole arms to the rear bracket 20 as hereinabove set forth, the plates 22 and 23 are maintained in loosely spaced relationship by the bolts 24. The reflector dipole arms 35 are slipped into the diverging channels and the bolts 24 are thereafter tightened to

produce an assembled rear or reflector dipole structure having two V-shaped dipoles with their apices adjacent each other and wherein the axes of the V's are in the same horizontal plane.

The central portion of plate or rear bracket member 21 is formed with openings 30 which permit connection of the end member 11 thereto. Flanges 31 and 32 are provided to embrace such end member 11. It will be observed in Fig. 3 that the central portion of plate 31 is bent along lines 33 and 34 so that the opposite channels or bracket portions are inclined toward each other and away from the front or fed dipole structure. In the form shown, the inclination of the reflector elements is approximately 15 degrees deviation from alignment, such inclination being suitable for the approximately 60 to 200 megacycles frequency range which the antenna is designed to accommodate.

As first explained herein, the most effective distance between the front and rear antenna elements is about a quarter of a wave length of any particular frequency which is accommodated or received. Considering, for the moment, the dipole arms 35 as complementary fed and reflector dipole arms, it will be observed that the effective distance between them increases as one approaches the respective ends. Thus, the outer ends of dipole arms 17 and 35 are spaced further away from each other than the inner ends at the cross beam 10. As the frequency accommodated or received by the antenna is decreased, a longer portion of the dipole arms is made effective use of, and the effective distance between the dipole arms 17 and 35 is correspondingly increased. The rearward inclination of the dipole arms 35 is most useful in producing a separation or spacing of the dipole arms 17 and 35 which is commensurate or proportional to the frequencies received. Whereas the antenna of my prior application exhibited this advantage by virtue of the pronounced forward inclination of the fed antenna elements, the instant structure amplifies the desirable results achieved by inclining the rear or reflector elements as described. A somewhat similar result could be secured by sharpening the angle of inclination of the front antenna dipole arms or rods 16 and 17, but it has been determined that this entails an adverse effect upon the shape of the lobe. On the contrary, rearward inclination of the dipole arms or rods 35 have no such tendency in that they do not disturb the optimum predetermined angle of inclination of the front dipole arms or rods 16 and 17. The angle of inclination of the rear, reflector dipole rods is considerably less than that of the front or fed dipole rods and such inclination forms a broad V with the apex thereof closer to the front dipole rods than the free ends of the arms as hereinabove explained.

What is claimed is:

1. A high frequency antenna comprising front and rear V-shaped antenna elements, said front antenna elements consisting solely of a single

pair of front V-shaped dipole structures, each dipole structure having its axis in a horizontal plane and the apices of the respective structures being substantially adjacent each other, an insulating member between said apices and to which the structures are connected, each of said front pair of V-shaped structures being inclined toward the other so that their axes form an obtuse angle, said rear V-shaped antenna elements consisting solely of a single rear pair of V-shaped dipole structures spaced from said front pair of dipole structures so as to act as reflectors therefor, the axes of the rear V structures being in the same horizontal plane and being inclined toward each other so as to form an angle, the direction of inclination of said rear V-shaped structures being rearwardly and the direction of inclination of said front pair of V-shaped structures being forwardly, the inclination of said rear V-shaped structures being less than that of said front pair of V-shaped structures.

2. An antenna comprising at least one front member and at least one rear member, said rear member being horizontally spaced from said front member so as to act as a reflector therefor, said front member being composed of forwardly inclined complementary dipole elements forming an obtuse angle between them, said rear member being composed of complementary dipole elements having their respective axes in the same horizontal plane and being inclined toward each other so as to form a second obtuse angle, the inclinations of the respective front member and rear member elements being in opposite directions, and the obtuse angle formed by the front member elements being smaller than the obtuse angle formed by the rear elements.

3. An antenna comprising at least one front member and at least one rear member, said rear member being horizontally spaced from said front member so as to act as a reflector therefor, said front member consisting solely of complementary dipole elements all of which are forwardly inclined so as to form an obtuse angle between them, said rear member consisting solely of complementary dipole elements all of which are rearwardly inclined and forming an obtuse angle between them, the inclination of said rear member elements being less than that of said front member elements.
